Fig. 4

FIG. 1 is a top plan view of a container for a laboratory weight set showing my new design as it appears in open position;

FIG. 2 is a front elevational view thereof;

FIG. 3 is a side elevational view as seen from the right side of FIG. 1 with the cover in a partially open position; and

FIG. 4 is a rear view thereof as seen in the direction of line 4—4 in FIG. 3, with the cover broken away for convenience of illustration.

Portions of the container, not shown, are conventionally plain and unornamented.

I claim:

The ornamental design for a container for a laboratory weight set as shown and described.
